Hugh James Oliver, and
Robert John Nash

By - B. Singer, Atty.

UNITED STATES PATENT OFFICE.

FRANCIS WILLIAM GOWER, HUGH JAMES OWEN, AND ROBERT JOHN NASH, OF BIRMINGHAM, ENGLAND.

MODE OF OR MEANS FOR ASSEMBLING AND TENSIONING THE WIRE STRIKING FACES OF METALLIC RACKETS AND THE LIKE.

Original application filed June 29, 1923, Serial No. 648,539. Divided and this application filed September 4, 1924. Serial No. 735,925.

To all whom it may concern:

Be it known that we, FRANCIS WILLIAM GOWER, a subject of the King of Great Britain, residing at "Dunoon," Russell Road, 5 Moseley, Birmingham, in the county of Warwick, England, HUGH JAMES OWEN, a subject of the King of Great Britain, residing at 110 Trinity Road, Birchfields, Birmingham, in the county of Warwick, England, 10 and ROBERT JOHN NASH, a subject of the King of Great Britain, residing at Oakfield Road, Cannon Hill, Birmingham, formerly of 46 Beaconsfield Road, Cannon Hill, Birmingham, in the county of Warwick, England, 15 have invented certain new and useful Improvements in the Mode of or Means for Assembling and Tensioning the Wire Striking Faces of Metallic Rackets and the like, of which the following is a specification.

20 The present invention has relation to a mode of or means for assembling and tensioning the flexible striking faces of metallic rackets and the like, and consists in firstly lacing the frame evenly in one direction, then temporarily distorting, straining, or bending it to tension such lacing, and then lacing crosswise to a desired tautness and releasing the frame so that by reason of its inherent resiliency or strength it tends to 25 re-shape itself and so increases the tension of the cross-wiring which holds the first mentioned wiring at the desired tautness.

30 The invention also consists in a metallic racket laced in this way with a suitable wire 35 lacing.

Apparatus for carrying out the above operation comprises in one instance a cramp adapted by a screw or equivalent device to force the sides of the racket frame inwardly so as temporarily to elongate it, after which the cramp is released or unscrewed to allow the frame to reshape itself.

40 Apparatus for carrying out the foregoing operation in another instance comprises a cramp adapted by a screw or equivalent device to effect an outward pull or opposed internal pressure on the extremities of the frame so as temporarily to elongate it, after which the cramp is released or unscrewed to allow the frame to reshape itself.

The present process and apparatus is particularly suitable for use in assembling and tensioning the metal striking faces of a metallic racket, the frame of which is formed from a strip or bar of solid section metal, 55 the extremities of which are directed outwardly to form the handle and wherein a spacing piece is fixed at the junction of the limbs with the frame and completes the latter. A frame of this character can be distorted or strained, and yet will return to its normal shape, and it is thus admirably suited for the purposes of this invention. Our invention is not restricted to wiring such a metallic racket, but may be applied in wiring any racket having a frame suitable for the purpose.

60 This specification is a division of our co-pending application for Letters Patent of the United States for "improvements in tennis racquets and the like," filed June 29th, 1923, Serial No. 648,539.

65 In order that this invention may be clearly understood and readily carried into practice, reference may be had to the appended 70 explanatory sheet of drawings, upon which:—

75 Figure 1 is a plan view of the apparatus for assembling and tensioning the wire striking face.

80 Figure 2, is a transverse section taken on line *c*—*c* of Figure 1.

85 Figure 3, is a plan view of a slightly modified apparatus.

90 In a convenient embodiment of the present invention, described with reference to Figures 1 and 2, the apparatus comprises a somewhat rectangular frame 1, having two parallel transverse rods or shafts 2 upon which the halves of the cramp are mounted, one half 3 being fixed, and the other half 4 being sliding and controlled by a screw 5, the thread of which operates in a tapped aperture, in the frame, and which screw is provided with a handle 6, as shown.

95 Each half of the cramp has a semi-elliptical cavity 7 cut therein, and the upper edge around each cavity is rebated or recessed at 8, adapted to receive the frame 9 of the racket 9, 10, indicated by the dotted lines.

The frame 9 of the racket is placed in these rebates or recesses 8, as shown in the Figure 1, the cramp tightened and the frame 9 compressed laterally, and thereby slightly elongated, this elongation being permitted by the shapes of the cavities in the cramp. The rebates or recesses 8 are of a depth adapted to leave the major part of the frame projecting so as to leave its striking face 10 apertures exposed. Pivotal holding clamps 11 are provided on the cramp halves and are adapted to be pivoted to rest upon the upper edge of the frame 9, to prevent its inadvertent separation from the cramp when 15 subjected to pressure. These pivotal clamps may be tightened by thumb screws. A wire tensioning device 12 may be employed, adapted to be assembled at any one of the four spaced positions 13 on the frame; or, 20 alternatively, four such members 12 may be employed. Such a tension device may involve a vertical rotatable spindle through which the end of the wire is adapted to be passed, and which spindle has a handle for 25 its rotation, and a pawl and ratchet mechanism 14 to prevent its backward rotation.

Single, two or more strand wire may be used for the striking face of the racket.

In operation, the frame of the racket 30 is first evenly wired longitudinally, as shown in the Figure 1, in any convenient manner, and the ends of the wire secured in the frame; the frame is then subjected to lateral pressure in the cramp, thus elongating 35 the frame and bringing the longitudinal wires in tension to a degree above that normally required in the finished racket.

While the frame is compressed, the transverse wires are threaded and brought to 40 an even tension slightly less than required in the finished racket. This can be done conveniently by the tensioning device 12 aforesaid. The ends of the cross wire are secured in the frame, and the latter is relieved of pressure and permitted to expand 45 itself laterally and thereby to tighten the transverse wires, and distribute the tension between the respective wirings. Usually rackets are of an oval shape and with such 50 shapes it is easier to distort the frame by lengthening the major axis than the minor one and consequently a lower tension in the cross wiring will hold and maintain the longitudinal wiring at a higher degree of 55 tension.

In another embodiment of the present invention, described with reference to Figure 3, the apparatus comprises a somewhat rectangular frame 1 having two parallel 60 transverse rods or shafts 2 upon which the halves 3 and 4 of the cramp are mounted, one half 3 being fixed and the other half 4 being slidable and controlled by a screw 5, the thread of which operates in a tapped 65 aperture in the slidable half, and which

screw is provided with a handle 6. Each half of the cramp has a semi-elliptical cavity cut therein, and at the centre part of each cavity an upwardly projecting arcuate rib 15 is provided. 70

The frame 9 of the racket is placed upon the present device, so that the ribs 15 engage within said frame at its extremities, and the cramp is operated and the frame thereby "stretched" or elongated, the sides 75 thereof moving slightly inwardly. The arcuate ribs are of sufficient length to bear evenly against a considerable portion of the ends of the racket frame to ensure that the pull is distributed as evenly as possible 80 over the longitudinal wires.

Pivotal holding clamps 16 are provided on the cramp halves and are adapted to be pivoted to rest upon the upper edge of the frame to prevent its inadvertent separation 85 from the cramp when subjected to pressure. These pivotal clamps may be tightened by thumb screws.

Four or other number of wire tensioning devices 12 may be employed upon the frame, 90 or alternatively one tension device may be employed, adapted to be assembled at any one of the four spaced positions on the frame, all as in the previous instance.

In operation, the frame of the racket is 95 firstly wired longitudinally in any convenient manner to a normal tension, and the ends of the wire attached to the frame. The interior of the frame is then subjected at its extremities to outward pressure, in 100 the manner aforesaid, thus elongating it and considerably tensioning the wires.

While the frame is strained, the transverse wires are threaded, and brought to a desired tautness conveniently by the rotary 105 tensioning device aforesaid. The ends of the wire are secured in the frame, the latter is released from pressure and permitted to expand itself with results similar to those described with reference to the device illustrated in Figures 1 and 2. 110

We claim:

1. A mode of assembling and tensioning the flexible striking face of a racket or the like, consisting in firstly threading or lacing the material of the striking face in the frame evenly in one direction, then temporarily distorting, straining, or bending the frame to tension such material, and then threading or lacing the frame crosswise to a desired tautness, and releasing the frame so that it tends to re-shape itself and suitably distributes the tension in the flexible striking face in the frame. 115

2. A mode of assembling and tensioning the flexible striking face of a racket or the like as in claim 1, wherein the desired distortion of the frame is effected by forcibly elongating the frame in the direction in which the first lacing runs to diminish the 120 125 130

lateral dimension of the frame, and wherein the cross-lacing of the frame is done whilst the latter is in this elongated condition.

3. Apparatus for use in assembling and 5 tensioning the flexible striking face of a racket or the like, comprising screw means for elongating temporarily the racket frame, said screw means also serving to retain said frame in elongated condition while a lacing 10 operation is performed on the racket.

4. Apparatus for use in assembling and 15 tensioning the flexible striking face of a racket, comprising means for engaging the sides of the racket frame so as to leave the lacing apertures therein clear, and screw means for bringing said engaging means nearer to each other and thereby elongating 20 said racket frame.

5. Apparatus for use in assembling and 25 tensioning the flexible striking face in an apertured frame of a racket, comprising a screw-operated device for distorting the racket frame while the latter is laced in one direction, with clamps on said device for holding the racket frame thereon during the 30 operation.

6. Apparatus for use in assembling and 35 tensioning the flexible striking face in an apertured frame of a racket, comprising a screw-operated device for distorting the

racket frame while the latter is laced in one direction in which a rotary tensioning device is incorporated for use in the operation of lacing the racket frame.

7. Apparatus for use in assembling and 35 tensioning the flexible striking face in an apertured frame of a racket, comprising in combination a rectangular frame with a pair of cross rods on which two complementary cramp parts are mounted, a screw working 40 in the frame to force the one cramp towards the other, and means on the cramp parts to engage opposite portions of the racket frame so as to distort the frame for the lacing operation when the screw is tightened up. 45

8. A racket or the like having a frame and a striking face formed by lacing wire through apertures therein, in which the longitudinal wiring is separate from the lateral wiring and in which one of said wirings is inserted while the frame is distorted sufficiently to tension the other wiring, and the wiring so inserted serves to retain the other wiring in desired tension when the frame is released from distortion. 50 55

In testimony whereof we affix our signatures.

FRANCIS WILLIAM GOWER.

HUGH JAMES OWEN.

ROBERT JOHN NASH.
